UNITED STATES PATENT OFFICE

WILLIAM D. LUCE, OF HAVERHILL, MASSACHUSETTS.

SPARK-PLUG TESTER.

1,248,877.

Specification of Letters Patent. Patented Dec. 4, 1917.

Application filed January 31, 1917. Serial No. 145,628.

To all whom it may concern:

Be it known that I, WILLIAM D. LUCE, a citizen of the United States, and a resident of Haverhill, county of Essex and State of Massachusetts, have invented an Improvement in Spark-Plug Testers, of which the following is a specification.

This invention relates to devices for testing the spark-plugs of internal-combustion engines, to determine if the plugs are sparking properly, said devices being commonly known as jump-spark testers. These devices have usually comprised a handle bearing a pair of contact arms, one being adapted to be grounded on the engine and the other to be held in contact with the plug which is being tested, said arm being electrically connected to spark-points which are held in proximity, but out of contact in a chamber formed in the handle and so arranged that the spark may be observed.

The conditions, under which devices of this character are likely to be used, vary considerably, so that, while such a device may be conveniently employed under some conditions, it cannot be as conveniently employed under others, and, as a result, their lack of adaptability is sometimes an objection.

The primary object of my invention is to provide a device of the character above referred to, which is readily adaptable to different conditions of use and which is also adapted to be reduced in size, so that it may be conveniently carried in the pocket.

I accomplish this and other objects of my invention, by the means shown in the accompanying drawing in which:

Figure 1 is a top view of a jump-spark tester embodying my invention.

Figs. 2 and 3 are views of opposite sides thereof.

Figs. 4 and 5 are sectional views on an enlarged scale, taken respectively at line 4—4 and 5—5 of Fig. 2.

Figs. 6 and 7 are elevations showing the device in different positions of use.

As shown in the drawing the device comprises a handle *a*, of wood or other suitable insulating material, in which a recess or chamber *a'* is formed adjacent one end and opens to the top side thereof, said recess having a concave mirror *b* secured on its bottom and having a preferably convex glass cover *c*, so arranged that the light from

the sparks, which may be formed in the chamber, will be reflected by the mirror onto the glass and the appearance thereof thus be intensified.

A pair of attaching plates *e* and *f* are secured to the opposite sides of the handle directly opposite the recess *a'* and a pair of contact arms *g* and *h* are pivotally mounted thereon, respectively, by means of tubular rivets *i*, *j*, arranged in axial alinement with each other, so that said arms may be swung thereon between directly opposite longitudinal positions, in one of which they project beyond the end of the handle in line therewith and in the other of which they lie alongside the handle, as respectively indicated in the dotted and full line positions of Fig. 1. The pivotal bearing of said arms is made sufficiently tight to hold said arms frictionally, in any position to which they may be adjusted and, preferably, small projections *g'* and *h'* are formed on the inner side of said arms and corresponding indentations are formed in the outer side of said plates *e*, *f*, to provide semi-frictional locks for said arms in the two longitudinal and two right angular positions to which they may be moved. One of the arms, *g*, is made much longer than the other, as is customary with such devices, and is of a length corresponding to the length of the handle, so that, when it is in the full line position of Figs. 1 and 3, it does not extend beyond the handle at any point, this being also true of the shorter arm *h*.

A pair of conductors in the form of screws *m*, *n*, are threaded in, and therefore electrically connected with eyelets *i*, *j*, respectively and extend into the recess *a'* into sufficiently close proximity to provide a spark gap, or to permit sparks to pass therebetween.

When the device is not in use, the contact arms *g*, *h*, will be folded at the side of the handle, as indicated by the full line positions of Fig. 1, so that it may be conveniently carried in the pocket and, when the device is to be used, the contact arms will be swung, usually, into positions either at right angles to the handle, or in line therewith, as in Fig. 6, according to conditions, a convenient arrangement for many conditions being to have one arm adjusted to the longitudinal position and the other to the right angular position, as in Fig. 7, so that

the end of the long arm may be placed in contact with the engine cylinder and the short arm be placed into contact with the spark plug terminal.

5 Under some conditions it is more convenient to have the long arm adjusted to the longitudinal position, and short arm to the right angular position with relation to the handle, and said arms may also be 10 placed in various intermediate positions, if conditions require it, and may be readily folded when the device is to be no longer used.

When a spark is passing between the 15 ends of the screws *m*, *n*, the light will be reflected by the concave mirror *b*, onto the glass *c*, considerably intensified, so that the fact as to whether the electrical connections between the plug, and the source of electrical supply, are in good condition, may be 20 readily determined.

I claim:—

1. A jump-spark tester comprising an insulating handle having an inspection chamber therein, adjacent one end, a pair of conductors extending into said chamber from opposite sides of the handle with their adjacent ends in sparking relation, a pair of contact arms pivotally mounted at opposite sides of the handle to swing about said conductors, respectively, between folded positions alongside the handle and positions of

use at different angles thereto and longitudinally thereof.

2. A jump-spark tester comprising an insulating handle having an inspection chamber therein adjacent one end, attaching plates secured to the handle at opposite sides of said chamber, a pair of contact arms having tubular pivots connecting the same to 40 said attaching plates respectively, to permit said arms to be swung between opposite longitudinal positions relative to the handle, and a pair of conductor screws threaded in 45 said pivots and extending into sparking relation with each other within said chamber.

3. A jump-spark tester comprising an insulating handle having an inspection chamber therein adjacent one end, a pair of contact arms having a frictional pivotal 50 connection with the handle at opposite sides of said chamber, to permit said arms to be swung between directly opposite positions longitudinally of the handle and to be held frictionally in said positions and in different 55 intermediate positions, and a pair of conductors having electrical connection with said arms, respectively, and extending into said chamber in sparking relation.

In testimony whereof, I have signed my 60 name to this specification.

WILLIAM D. LUCE.
